COMB

Samuel J. Golden, 2095 Grand Concourse, 180th St.,
Bronx, N.Y.

Filed Mar. 21, 1961, Ser. No. 64,412

Term of patent 14 years

(Cl. D86—8)

FIG. 1 is a side elevational view of a comb, showing my new design.

FIG. 2 is a bottom plan view.

FIG. 3 is another side elevational view showing the side opposite to that seen in FIG. 1; and

FIG. 4 is a sectional view on line 4—4 of FIG. 1, on a larger scale.

I claim:

The ornamental design for a comb, as shown.
